CLAIM

The ornamental design for a can shaped telephone booth, as shown and described.

DESCRIPTION

FIG. 1 is a perspective view of the can shaped telephone booth showing my design.

FIG. 2 is a front view of the can shaped telephone booth.

FIG. 3 is a top view of the can shaped telephone booth.

FIG. 4 is a bottom view of the can shaped telephone booth.

FIG. 5 is a back view of the can shaped telephone booth.

FIG. 6 is a right side view of the can shaped telephone booth; and,

FIG. 7 is a left side view of the can shaped telephone booth. The broken lines are for illustrative purposes only and form no part of the claimed design.
